UNITED STATES PATENT OFFICE.

EDWIN E. SLICK, OF PITTSBURGH, PENNSYLVANIA.

HOTBED.

1,106,478.

Specification of Letters Patent. Patented Aug. 11, 1914.

Application filed January 28, 1908. Serial No. 413,045.

To all whom it may concern:

Be it known that I, EDWIN E. SLICK, of Pittsburgh, in the county of Allegheny and State of Pennsylvania, have invented a new and useful Improvement in Hotbeds, of which the following is a full, clear, and exact description, reference being had to the accompanying drawings, forming part of this specification, in which—

10 Figure 1 is a top plan view showing a double hot bed constructed in accordance with my invention; Fig. 2 is a sectional end elevation of the same on the line 2—2 of Fig. 1; Fig. 3 is a longitudinal section on a 15 larger scale of one of the helical or spiral screws or worms, forming part of this invention; Fig. 4 is an end view of the screw shown in Fig. 3; Fig. 5 is a sectional side elevation on a larger scale showing a portion of the turning mechanism by which the 20 rotating skids or supports forming the hot bed are rotated.

My invention relates to storage beds and similar apparatus employed in rolling mills 25 in handling metal bars and similar materials, and it more particularly relates to hot beds having means for transferring such materials transversely of their length across the width of the hot bed.

30 The object of the invention is to provide a hot bed having improved means for moving the bars across the width of the hot bed, while the bars are being cooled from the hot state in which the rolling operation is completed to a cold state in which they can, if desired be handled by hand.

Another object of the invention is to provide improved mechanism for actuating the apparatus employed in carrying the bars 40 across the width of the hot bed and to provide improved means by which the bars are moved on to the hot bed from the rollers of the delivery table and on to the rollers of the receiving table from the rotary supports or skids, forming the hot bed.

45 A further object of the invention is to provide improved means for keeping the bars in position on the rollers of the delivery table while being fed forwardly on these rollers to a point opposite the hot bed, and means for retaining and collecting the bars as they are successively removed from the hot bed, and for depositing the collected bars on the rollers of the receiving table.

50 In the drawings, 2, 2, represents the rollers of the delivery tables on which the materials

are carried from the reducing rolls of a rolling mill or other point of supply to a point alongside of the hot bed from which they are automatically transferred to the hot bed. 60 The rollers 2 are mounted on the opposite overhanging ends of suitable shafts rotatably carried in bearings 3. A stop 35 is removably secured on the tables formed by the rollers 2, against which the bars strike as 65 they are fed forwardly on these tables. The stop is removably secured in place so as to permit of its being located at various points in the length of the tables to suit the different length of the materials handled on 70 the tables. The shafts are provided with sheave wheels 4, these wheels being driven by means of the endless rope or cable 5, which extends between the sheave wheels 6 and 7, which are located at opposite ends of 75 the hot bed. The sheave wheel 6 is driven by any suitable type of motor, not shown, and the wheel 7 is adjustably mounted so as to regulate the tension on the driving rope 5.

Extending on opposite sides of the tables 80 formed by the rollers 2 are the hot beds which are formed of a series of rotating skids 8, having means thereon for pushing the materials lengthwise of the skids. The ends of these skids are journaled in suitable bearings 9, and on their outer ends are spur pinions 10, which mesh with and are rotated by spur gears 11, which are rotatably mounted on stub shafts 12. Each of the spur gear wheels 11 is provided with 90 ratchet teeth 13, and on each of the shafts 12 is a rocking arm 14. One end of the arm 14 is provided with a pawl 15, which engages with the ratchet teeth 13 on the wheels 11, the opposite end of the arms 14 being 95 connected together by means of links 15', and means for adjusting the length of these links is provided by the sleeve nuts 16. One end of the link 15' is connected to a crank 17 on the slow-down gearing 18, 100 which is connected with the rotary motor 19. On the outer side of each hot bed formed by the rotating skids 8 are receiving tables formed by the rollers 20, these rollers being driven through bevel gears 21, 22, and line 105 shafts 23, which shafts are connected through slow-down gearing 24 with table-driving motors 25.

The rotating skids 8, forming the hot bed, are provided on their ends with inclined wings 26 and 27, these wings being arranged to lift a bar from the rollers 2 and

cause it to slide into engagement with the root of the threads formed on the skids 8 at each revolution of the skids. The receiving ends of the skids 8 are provided with spaced 5 apart encircling guide collars 8^a which serve as side guards to guide the metal bars or shapes as they are delivered lengthwise on the rollers 2, the wings 26 on this end of the skids 8 being below the plane of the top 10 of the bed formed by the skids except when elevating the bars in transferring them side- wise from the rollers 2 to the skids 8. The outer ends of the skids are also provided with inclined supports 28, upon which each 15 bar slides when lifted by the wings 27. The lower outer ends of the supports 28 have rocking arms 29, provided at suitable intervals in the length of the hot bed, these arms serving as stops to retain and collect the bars 20 on the supports 28, until such time as it is desired to have these bars discharged upon the rollers 20, forming the receiving table. The lower ends of the arms 29 are connected together by means of links 30, these links 25 being connected to the cranks 31 on the slow- down gearing 32, connecting the links with the operating motors 33.

In the operation of my improved apparatus, the bars or other materials are delivered endwise on the rollers 2 from a 30 point of supply, until they are opposite the hot bed formed by the revolving skids 8. As the bars are carried forward on the rollers 2, they come into engagement with the stop 35 and are brought to rest in position to be removed from the rollers 2 on to the skids 8. The skids 8 are intermittently rotated by the motors 19, through the connecting ratchet mechanism, and as 35 the wings 26 on the skids 8 approach a vertical position, the bars are successively lifted from the rollers 2 and slide down the inclined edges of the wings 26 on to the skids 8. As the skids rotate, the bars are 40 then fed forwardly across the length of the skids, and upon reaching the ends of the skids, come into engagement with the inclined edges of the wings 27. When these wings approach a vertical position, the bars 45 are again lifted and slide forwardly on to the supports 28, the bars preferably being held at this point by the stops 29, although these stops may be omitted, if desired. After the desired number of bars have been 50 collected against the stops 29, the stop operating mechanism is actuated to move the stops out of the path of the metal and allow the bars to slide down the inclined supports 28, on to the rollers 20 of the receiving tables. The cooled metal bars are then 55 carried endwise on the rollers 20 from in front of the hot bed. Provision for momentarily holding the wings 26 and 27 in their vertically upright position is made by means 60 of the springs 36 which press against the 65

square sides 37 on the hubs of the wheels 11, as is best shown in Fig. 5.

The advantages of my invention will be apparent to those skilled in the art. There are no lifting parts, necessitating the lifting of all of the bars on the tables on the hot bed, in moving them forwardly across the width of the hot bed. As the bars are moved gradually across the width of the hot bed by the intermittent 70 rotation of the skids or supports on which these bars are carried, they will be moved forwardly endwise at the same time. This gives constantly changing points of contact on the bars and prevents the formation of 75 black spots at the points of contact as is the case where the bars do not move lengthwise, while being transferred across the width of the hot bed.

The apparatus is simple and is easily kept 80 in repair. Modifications in the construction and arrangement of the parts may be made without departing from my invention as defined in the appended claims. The angle of the thread of the rotating skids or screws 85 90 may be changed as is desired.

I claim:

1. A hot bed comprising in combination, a series of lengthwise parallel rotary bar supporting and transferring members, said 95 members having screw threads thereon, and means for rotating said members, said means having spur pinions on the supporting and transferring members, spur gear wheels meshing with the pinions, ratchet wheels 100 for turning the spur gear wheels, a series of rocking arms having pawls engaging the ratchet wheels and means for rocking the arms to thereby actuate the supporting members in transferring bars across the 105 width of the hot bed; substantially as described.

2. A hot bed comprising in combination, a series of lengthwise parallel rotary screw threaded bar supporting members, the screw 110 threads engaging with and moving bars on the supporting members from one end to the other of said members, and means for rotating said members in unison, said means including pinions on the supporting members, gears meshing with the pinions and connecting the supporting members in pairs, ratchets and pawls for turning said gears and means for intermittently actuating the ratchets and pawls to rotate the supporting 115 120 members; substantially as described.

3. In a hot bed for metal bars, a bar supporting and transferring member having a helical thread thereon, and having guide collars at one of its end portions, and means 125 for rotating said member.

4. In a hot bed for metal bars, a bar supporting and transferring member having a helical thread thereon and having guide collars at one of its end portions, a lifting 130

wing extending between the collars and to the adjacent end portion of the thread and arranged to lift and transfer the bars sideways when the supporting member is rotated, and means for rotating said member.

5. A hot bed comprising in combination, a series of lengthwise parallel rotary screw threaded bar supporting members, said screw threads engaging with and moving 10 bars on the supporting members from one end to the other thereof and means for rotating said members in unison, said means including gearing connecting the support-

ing members in pairs, a ratchet and pawl operatively connected to the gearing, swinging arms on which the pawls are mounted, a rod connecting the arms and means for operating the rod to intermittently actuate the arms to turn the supporting members; substantially as described.

15 In testimony whereof, I have hereunto set my hand.

EDWIN E. SLICK.
